United States Patent Office

Des. 207,613
Patented May 9, 1967

207,613

DISPLAY STAND

Clayton E. Ratcliff, Cincinnati, Ohio, assignor to The Kroger Co., Cincinnati, Ohio, a corporation of Ohio

Filed Aug. 18, 1966, Ser. No. 3,527

Term of patent 14 years

(Cl. D80—9)

Fig. 1

I claim:

The ornamental design for the display stand, as shown and described.
